UNITED STATES PATENT OFFICE.

PETER BARCLAY, OF WINTHROP, MASSACHUSETTS.

SAFETY WATER-GAGE.

SPECIFICATION forming part of Letters Patent No. 369,904, dated September 13, 1887.

Application filed May 15, 1886. Serial No. 202,275. (No model.)

To all whom it may concern:

Be it known that I, PETER BARCLAY, of Winthrop, in the county of Suffolk and State of Massachusetts, have invented a new and 5 Improved Gage-Cock, of which the following is a full, clear, and exact description.

My invention relates to the construction of a gage-cock wherein the parts are so arranged that the valves will close automatically and 10 prevent the outward passage of steam or water in case the glass sight-tube should be accidentally broken.

Reference is to be had to the accompanying drawings, forming a part of this specification, 15 in which similar figures of reference indicate corresponding parts in both the views.

Figure 1 is a central sectional view of the upper cock of a water-gage, said cock being constructed in accordance with the terms of 20 my invention, and Fig. 2 is a similar view representing the lower part of a water-gage.

Referring now to the construction illustrated in the drawings, 10 represents the main body or barrel of a water-gage cock, which is preferably formed, as illustrated, for direct connection to a boiler, a portion of which is shown at 20; but it will of course be understood that the cock might be connected to the boiler through the medium of a thimble.

30 The barrel or body of the cock is formed with a valve-seat, 2, and a valve, 3, which is preferably in the form of the frustum of a cone, and which is provided with a downwardly-extending guiding-stem, 4, which is arranged in connection with said seat, the stem 4 riding in a properly-arranged socket, 5.

In connection with the valve arranged as described I employ a valve-setting stem, 6, that projects from the lower end of a screw, 7, 40 said screw being mounted in a properly-arranged socket and entering the valve-chamber through a stuffing-box, 14, arranged in the ordinary well-known manner. Upon the outer end of the screw 7 there is a hand-wheel, 45 15, and, if desired, a spiral spring, 8, may be

coiled about the stem 6, which stem is of less diameter than the main body of the screw, as clearly shown, so that one end of the spring may abut against the end of the screw proper, while the other end of the spring will abut against 50 the upper face of the valve 3.

In operation we will suppose that the valves 3 are in the position in which they are shown in the drawings—that is, pressed against their seats 2 by the pressure of the steam or water 55 within the boiler 20. Then if the screws 7 are advanced so that the lower ends of their stems 6 abut against the upper faces of the valves 3, the said valves will be moved away from their seats 2, thus admitting the steam or water 60 within the gage-cock and within the sight-tubes 16, and if, after the water and the steam is so admitted to the sight-tube, the screws 7 are turned to withdraw the stems 6 from the faces of the valves 3, the steam or water pressure upon each face will be equal, and the weight of the valves themselves will prevent the valves from moving to their seats except at times when the tube 16 breaks, and immediately upon the breaking of such tube the 70 equality of pressure would be destroyed and the pressure upon the under faces of the valves would force them forward against their seats, thus closing the passage to the glass sight-tube.

The springs 8 aid in holding the valves from 75 their seats; but in practice I have found that the spring may be entirely dispensed with.

Having thus fully described my invention, I claim as new and desire to secure by Letters Patent—

The combination, with a valve formed with a stem, 4, and mounted in a socket, 5, of a cock body or barrel formed with a seat, 2, a screw, 7, mounted in said body, a stem, 6, carried by the screw, and a spring, 8, surrounding the stem, substantially as described.

PETER BARCLAY.
